A. STUFFLEBEAM

DRINK MIXER

Filed August 11, 1924

Albert Stufflebeam,
INVENTOR

BY

ATTORNEY

UNITED STATES PATENT OFFICE.

ALBERT STUFFLEBEAM, OF PARIS, ARKANSAS.

DRINK MIXER.

Application filed August 11, 1924. Serial No. 731,382.

To all whom it may concern:

Be it known that I, ALBERT STUFFLEBEAM, a citizen of the United States, residing at Paris, in the county of Logan and State of Arkansas, have invented a certain new and useful Invention in Drink Mixers, of which the following is a specification, reference being had to the accompanying drawings.

- 10 This is an invention, electrically, for the purpose of mixing drinks at the so called "soda fountain." This is a day of mixed drink demand, and various devices have been used, the vaporization from which has 15 resulted in rusting to a point where the same has been rendered inefficient and shorting to a point where the same has been rendered inefficient, if electrically controlled.

The invention herewith has been so designed and the arrangement is such, that the zone of "mixture" is both remote from and mechanically protected from the operating mechanism, and not alone that, but the construction is such that the driving parts 25 are so protected that operation does not splash the operator or that which is by him worn.

Other objects of the invention, will, of course, appear from a further and more 30 complete reading of the following specification.

On the drawing accompanying and forming a part of the specification,

Figure 1 is an elevational view, in sectional detail of the structural device, indicating a glass, with mixer therein, and means electrically portrayed for operating the mixer.

Figure 2 is an elevational and detail view 40 of shaft and pinion operation.

In these several views, similar characters of reference indicate similar parts.

A footed standard 3, having a laterally extended foot or platform 4, and serving 45 as a base, is hollow to telescopically receive a post 5 partly depending into said standard, and buoyed by a spring 6 internally couched in the standard 3.

The tension or urgency of this spring is 50 to be measured in view of other parts to be presently named, so that at any point of upward delivery of the said parts or their pressure downward, the balance will be equalized.

Within the standard 3, also the post 5, is a conduit 7 passing into the standard 3,

in the usual manner as for instance through a rosette 8 and from thence cabled in the usual manner as at 9 to a suitable connection.

60

Supported from the post 5 is a housing 10 in which is journaled a motor 11 fed by the conduit 7 which is intervened by an automatic switch 12, which closes when the post is in its lowermost position, for instance as 65 shown in the drawing. Thus in giving the contact the current is transmitted from source to motor, the latter then operating.

The interior of the housing 10 is under division by an arbor 13 in which the shaft 70 14 of the motor is journaled, and to the other side of this arbor is a gear 15, meshing with which are pinions 16 and 17 the placing and use of which will now be set forth.

Two shafts are employed, one 18 a solid internal shaft, and the other a hollow shaft 19 surrounding the said solid shaft. The solid shaft protrudes through each end of the hollow shaft, and at the upper end 80 enters a bearing 20 in the housing 10. The outer shaft is borne in a bearing 21 at the base of the interior of the housing 10 and the pinion 16 is applied to one shaft and the pinion 17 to the other. Now then when the motor operates the gear 15 urges the pinions 16 and 17 and in opposite directions, thus turning one shaft in one direction and the other shaft in the other direction.

Attached to each shaft are axially angled equidistantly disposed paddles the angles of one set being in opposed angle to those of the other set, and by virtue of the construction set forth naturally rotate in opposed directions. These are shown lowered into the container 22, and so treat the contents therein as to give the same an upward and downward disturbing efficiency, simultaneously thus switching the contents in opposed and intermixing relation. This 100 forms a mixture of the substances, that in no other way can be fully gained, and especially in the heavier and lighter substances that form parts of mixed content.

This feature is of importance since there 105 is obtained a homogeneous mixture that makes a substance well welded together into a new unitary formation, giving a balanced taste and colour.

It is understood of course, from the above 110 that the elevation of the housing 10 causing a switch-break will render the device

2
inoperative, while depending the device with the paddles into the container will cause the paddles to rotate in opposed directions in the container, giving the results stated.

Having thus described this invention, I claim:

In a drink mixer, a base for supporting the receptacle in which the liquid is to be mixed, 10 a telescopic standard mounted thereon, an elongated casing mounted thereon, said casing being divided by a partition wall hav-

ing a bearing, a motor on one side of said partition, bearings on the upper and lower side of the casing and on the other side of the partition, concentric shafts journaled in said bearings, agitator blades upon said shafts, and means to drive said shafts in opposite directions simultaneously.

Signed at Paris, in the county of Logan 20 and State of Arkansas, this 14 day of December, in the year of our Lord, nineteen hundred and twenty-three.

ALBERT STUFFLEBEAM.
